CLAIM

The ornamental design for a water recreational float, as shown and described.

DESCRIPTION

FIG. 1 is a front perspective view of a water recreation float showing my new design; and

FIG. 2 is a front view thereof.

FIG. 3 is rear view thereof.

FIG. 4 is a left-side view thereof.

FIG. 5 is a right-side view thereof.

FIG. 6 is a top plan view thereof; and,

FIG. 7 is a bottom plan view thereof.

The broken lines depict portions of the article that form no part of the claimed design.
